UNITED STATES PATENT OFFICE.

HUGO GOLDSMITH, OF CINCINNATI, OHIO, ASSIGNOR TO THE P. GOLDSMITH SONS COMPANY, OF CINCINNATI, OHIO, A CORPORATION OF OHIO.

FOOTBALL PANTS.

Application filed January 12, 1921. Serial No. 436,633.

To all whom it may concern:

Be it known that I, HUGO GOLDSMITH, a citizen of the United States, and a resident of the city of Cincinnati, in the county of 5 Hamilton and State of Ohio, have invented certain new and useful Improvements in Football Pants, of which the following is a full, clear, and exact description, reference being had to the drawings forming part 10 of this specification.

My invention relates to football pants equipped with thigh guards.

In pants of this character, I have found it to be very valuable to prevent the thigh 15 guard from slipping out of place, by means of a member secured to the pants leg, and serving to draw the material at the front of the leg very tightly and snugly against the leg. Furthermore a very tight material 20 at the thigh portion of the leg in front of the wearer will make it difficult for an opponent to get a grasp on the material of the pants as in a game of football. It is accordingly my object, partly in connection 25 with football pants which have the fiber thigh guards supported directly by the material of the pants leg, to provide a means for stretching the cloth at the front of the leg very tightly against the wearer. It is 30 also my object to make such a stretching device from elastic material, which is at the same time adjustable, and as one of my advantages to provide for the use of an all-rubber elastic piece as distinguished from 35 elastic tape of ordinary character.

These objects I accomplish by that certain construction and arrangement of parts to be hereinafter more specifically pointed out and claimed.

40 In the drawings,

Figure 1 is a front elevation of a pair of football pants, showing the front of one of the legs broken away.

Figure 2 is a rear view of the said pants.

45 Figure 3 is a section on the line 3--3, of Figure 1.

Figure 4 is a detail elevation showing the elastic device of my invention. Figure 5 is a front view of the pants in use.

50 While the exact form of thigh guard is not essential to my invention, I prefer to use that form of guard in my Patent No. 1,264,916, dated May 7, 1918. Thus, in the pants leg 1, I mount by means of laces 2, 55 and eyelets 3, a thigh guard 4. This thigh

guard consists of concave fiber strips 5 stitched into a pad with a felt inner lining 6 and a cloth outer lining 7.

The pad is thus suspended adjustably by the laces 2 thereon being tied through the eyelets 60 3 on the pants, there being no other point of attachment on the said thigh guard, and the thigh guard being located in front of the leg, as is usual in this style of construction. 65

While the device of my invention to be described below is of advantage where used with harness such as I show in my patent above referred to, it is of particular value in the construction above described. The 70 construction which I have now described is shown in my Patent No. 1,225,799, dated May 15, 1917.

As has been stated, the object of my invention is to draw the cloth at the front of the 75 pants leg tightly over the thigh guard thereby holding the thigh guard firmly in place against dislodgement, due to the roughness of play, and presenting a taut surface, thereby eluding the grasp of the opponent. I 80 show and describe but one embodiment illustrative of my invention.

To the seam at the inside of the leg, I saw a loop 8 of stout tape, or such material as may be desired, preferably non-elastic. 85 To this loop of tape, I hitch a stout all-rubber band 9. Across the back of the pants leg, at this point I mount a wide strip 10 of tape, so as to form a casing through which the rubber band is led. 90

In the opposite seam of the pants, I mount a pair of eyelets 11, and pass a cord 12 through the eyelets and through the rubber band. By tying the cord, or such other lacing as is used, tightly or loosely, the tension of 95 the rubber band may be increased or decreased.

The above structure, therefore, provides an elastic and adjustable means for pulling the pants leg very tightly at the front, with 100 the attendant advantages above noted.

Other means of accomplishing my object will be apparent to those skilled in the art, without the exercise of inventive skill.

Having thus described my invention, what 105 I claim as new, and desire to secure by Letters Patent, is:—

1. In foot ball pants or the like, a thigh guard positioned at the front of the leg, a trouser leg over said thigh guard, and elastic 110

means secured across the back of said leg and adapted to draw the cloth of the trouser tightly against the said thigh guard, for the purpose described.

5. 2. In foot ball pants or the like, a thigh guard positioned at the front of the leg, a trouser leg over said thigh guard, said guard being mounted on the said trouser leg, and elastic means secured across the back of said 10 trouser leg, and adapted to draw the cloth thereof, and the thigh guard, tightly against the leg for the purpose described.

3. In a foot ball pants or the like, a thigh guard positioned at the front of the leg, a 15 trouser leg over said thigh guard, and adjustable means secured across the back of said leg, and comprising at least in part, an elastic portion, said means being adapted to draw the cloth of the trouser leg tightly 20 against the said thigh guard.

4. In a foot ball pants or the like, a thigh guard positioned at the front of the leg, a trouser leg within which said thigh guard is 25 adjustably suspended at its upper end, and an elastic band secured across the back of the trouser leg, to draw the cloth of the trouser leg tightly against the said thigh guard.

5. In a foot ball pants or the like, a thigh guard positioned at the front of the leg, a 30 trouser leg within which said thigh guard is located, and an elastic band secured to the seams of the trouser leg, and extending across the back thereof, and adapted to draw the cloth of the trouser leg tightly against 35 the thigh guard.

6. In a foot ball pants or the like, a thigh guard positioned at the front of the leg, a 35 trouser leg within which said thigh guard is located, a casing formed across the back of 40 the leg and an adjustable tightener secured to the trouser and extending across through said casing, whereby the cloth at the front of the trouser leg may be tightly drawn over the wearer.

7. In a foot ball pants or the like, a thigh 45 guard positioned at the front of the leg, a trouser leg within which said thigh guard is located, a casing formed across the back of the leg and an adjustable tightener extending across through said casing and adjustably held to the trouser leg, whereby the cloth at the front of the trouser leg may be 50 tightly drawn over the wearer, said tightener comprising an elastic band, and tapes secured in the seams of the trouser leg, and 55 engaging said band, for the purpose described.

8. In a football pants or the like, a thigh guard positioned at the front of the leg, a trouser leg within which said thigh guard is 60 located, a casing formed across the back of the leg and an adjustable tightener extending across through said casing and adjustably held to the trouser leg, whereby the cloth at the front of the trouser leg may be 65 tightly drawn over the wearer, said tightener comprising an elastic band, and tapes secured in the seams of the trouser leg, and engaging said band, for the purpose described, one of said tapes being adjustably 70 secured in its trouser leg seam.

9. In a football pants or the like, a thigh guard positioned at the front of the leg, a trouser leg within which said thigh guard is 75 located, a casing formed across the back of the leg and an adjustable tightener extending across through said casing and adjustably held to the trouser leg, whereby the cloth at the front of the trouser leg may be tightly drawn over the wearer, said tightener comprising an elastic band, means for 80 securing said band to the one seam of the trouser leg, eyelets in the other seam of the trouser leg and lacing or the like, to secure the band adjustably to said eyelets, as and 85 for the purpose described.

HUGO GOLDSMITH.
